VALUE TRANSFERRING MECHANISM

Friedrich Pott, Thuringia, Germany, assignor to
Mercedes-Buromaschinen-Werke Aktiengesell-
schaft, Benhausen, Thuringia, Germany

Original application September 23, 1931, Serial
No. 564,643. Divided and this application Au-
gust 25, 1933, Serial No. 636,838. In Germany
November 28, 1936

7 Claims. (Cl. 235—144)

This invention relates to a resetting mechanism, and is a division of my U. S. application, Ser. No. 564,643, filed on September 23, 1931.

Resetting mechanisms of this kind have already 5 become known with regard to such machines, in which the numeral wheels of all decimal places of the accumulator are arranged on the same shaft.

The object of the invention is to provide a 0 resetting mechanism on such machines, in which an individual shaft is arranged for each decimal place of the accumulators.

Preferably the resetting mechanism may be 5 provided with a second resetting operating member for the resetting of the revolution counter, whereby both resetting members, viz. that of the accumulator and that of the revolution counter may be either made operative individually or simultaneously by special keys, which in their turn 10 control a common power operated clutch.

In the drawings, one form of construction according to the invention is illustrated by way of example as applied to a Mercedes Euklid calculating machine as described in U. S. Patent 1,011,617.

Fig. 1 shows a front view in perspective of the machine in which for the sake of clearness the cover plates of the carriage and of the machine are partly removed.

Fig. 2 shows a perspective view of the main driving shaft, with the resetting-clutch, viewed in the direction of the arrow b of the Figure 1 with the parts separated out from one another.

Fig. 3 shows a plan of the numeral wheels of 5 the revolution counter on an enlarged scale for the purpose of better illustration of the individual mechanisms.

Fig. 4 shows a longitudinal section through the carriage and along the lines 4a—4a, 4b—4b, and 0 4c—4c in Fig. 9 viewed in the direction of the arrows at the ends of the sectional lines in Fig. 9. The sections corresponding to lines 4a—4a, 4b—4b and 4c—4c of Fig. 9 are designated in Fig. 4 by a—a, b—b and c—c.

Figures 5 and 6 show on an enlarged scale a section and in two different positions of a lock 5 for preventing overthrow of the resetting device of the revolution counter along the line 4a—4a of Figure 9, viewed in the opposite direction of the arrows at the ends of the sectional line 4a—4a. Fig. 6 shows the position of the parts immediately after the completed resetting process.

Figure 7 shows a side view of a detail in Figure 4 viewed in the direction of the arrow c.

Figure 8 shows a side view of a section along

the line 8—8 in Figure 4, viewed in the direction of the arrows at the ends of said line.

Figure 9 shows a section along the line 9—9 in Fig. 4, viewed in the direction of the arrows at the ends of said line. 5

Figure 10 shows a perspective view taken from the righthand front of the machine of the keys for the accumulator and revolution counter resetting device in which the resetting clutch for the sake of clearness is drawn out of its true 10 position towards the right.

Fig. 10a is a side view of the resetting clutch viewed in the direction of the arrow a of Fig. 10.

The motor (not shown) is removably attached 15 on the rear side of the machine. In Fig. 1, only the cable of the motor is shown. The rotations of the motor, revolving in the direction of the arrow e1 (Fig. 10) are transferred through a worm 1, and a worm wheel 2, to a driving shaft 3, Figure 10. The driving shaft 3 is thus rotated in 20 the direction of the arrow e, Figures 2 and 10.

On the right hand side of the machine, Figures 1 and 10 a key board resetting key 6 is disposed, which is indicated by R, an accumulator resetting key 7 which is indicated by R and a revolution counter resetting key 8 which is indicated by Rrc. 25

The shaft 3, Figures 2 and 10 is as already 30 mentioned driven in the direction of the arrow e by the worm wheel 2 which engages with the worm 1.

On the driving shaft 3, a cam 20, Figure 10, formed with a conical circumference, is non-rotatably mounted, said cam coacting with an arm 21, of a two-armed contact lever 22, the purpose of which will be later described in a more detailed manner. The arm 21 in its rest position lies on the conical circumference 23 of the cam 20, and is held in this position by means of a spring 295b attached at one end to a lug 21a 40 of the arm 21, of the lever 22, and at its other end to a nose 295a of the lever 22.

On the driving shaft 3, Figures 2 and 10, the 45 resetting clutch 83 is disposed which is rotatably mounted on the driving shaft 3, while the cam 24, is fixed on the shaft 3. The clutch disc 85 is fastened to the housing 83 by means of screws 86, Figure 10, which engage with holes 87, Figure 2, and is provided with a hole 88, into which the driving shaft 3 projects so far that it terminates 50 with the side of the cover disc 85 remote from the clutch housing 83. In the housing 83, a clutch pawl 89, Figure 2, is swingably mounted by means of a bolt 90 arranged between the clutch housing 83 and the cover disc 85, and 55

disposed in the holes 91 and 92, and the pawl is acted upon in the clockwise direction, by a spring 95, which is attached to a nose 93 of the pawl 89, and to a pin 94, of the housing 83. A nose 96 of the pawl 89 abuts on a nose 97 (Figure 10, the clutch 83 is here for the sake of clearness drawn out on the right) which is formed on an arm 98 of a clutch lever 100 (Fig. 10) swingably mounted on a screw 99. The nose 101, Figure 2, of the pawl 89, is thereby held out of engagement with the nose 102 of the cam 84, since a pawl 104 engages with a groove 103 formed in the clutch housing 83. The pawl 104 is at one of its ends of fork-like construction, and is swingably mounted in a ring groove of the shaft 89. By means of a spring 105, which on one side is attached to a nose 106 of the pawl 104, and on the other side is secured to a bolt 50a, arranged in the machine frame, the pawl 104 is acted on in the clockwise direction, Figure 2. In the housing 83, a groove 107 is further provided, which will be later described in a more detailed manner.

On the cover disc 85, a pin 108 is provided, to which a rod 109, Figure 10 is pivoted (the rod operating the resetting device of the accumulator and revolution counter A and RC, Figure 1).

Resetting clutch for the accumulator and for the revolution counter

On the housing 83, there is provided a pin 110, Figures 2 and 10 which acts on a two-armed lever 112, swingable round the point 111 on the machine frame. The lever 112 is acted upon by means of a spring 115, in the anticlockwise direction, Figure 10, the spring being attached to the nose 113 of the lever and to the pin 50a fixed in the machine frame. In its rest position, it lies with its horizontal arm on two levers of the resetting mechanisms for the accumulator and revolution counter.

If one of the keys 7 or 8 is depressed—in the present example the key 7 is depressed—the coupling lever 100 is swung clockwise (as shown in Figure 10a) through the parts 515, 515b, 520, 522a (Fig. 10) whereby the nose 101 (Fig. 2) of the pawl 89 enters the path of the nose 102 of the cam 84 secured to the driving shaft 3. Since the motor contact 300, 302 (Fig. 10) is closed simultaneously with the depression of the key 7, the driving shaft 3 will be rotated through the gears 1, 2 and the clutch housing 83 (Fig. 10a) rotated in the direction of the arrow e whereupon at the beginning of the rotation, the pawl 104 is swung clockwise against the action of the spring 105. During the rotation of the housing 83, the pawl 104 moves on the periphery of the clutch housing. As soon as the key 7 is released, the nose 97 of the lever 100 again enters the path of the nose 96 of the pawl 89. Prior to the completion of one of the complete rotations of the clutch housing 83, the nose 97 of the lever 100 acts on the nose 96 of the pawl 89 whereby it is swung anti-clockwise against the action of the spring 95 (as shown in Fig. 2). The nose 101 of the pawl 89 is now disengaged from the nose 102 of the cam 84. Owing to the torque of the clutch casing 83, the latter will be rotated until the pawl 104 again engages in the groove 103 of the clutch casing 83 whereby a rearward rotation of the latter is prevented and it is held in its position of rest.

On the right-hand side of the machine, besides the addition key stem 239, Figure 1, and the subtraction key stem 353, the mechanism for releas-

ing the keys depressed in the keyboard K, the resetting mechanism of the revolution-counter RC, and of the accumulator A are also arranged, which will be described in detail in the following.

Keyboard releasing mechanism

The key 6 for releasing the depressed keys, which bears the reference R, Figures 1 and 10, is provided on a stem 505, which is guided in the guide plate 238 and by means of a screw (not shown) engaging an elongated hole 506 in a vertically slidable manner. A spring 507 connected to the stem 505 holds the slide 505 in its normal position, which is determined by the impact of the end 508, of the elongated hole 506, against the screw (not shown) engaged therewith. The stem 505 acts in its downward movement with its face 509 on the face 510, of an arm 511, of the key resetting rail 318 swingable on the shaft 261. The rail 318 lies with its face 318a, Figure 10, against projection 514a, of the known key locking bar 514.

Resetting mechanism for the accumulator

The resetting key 7, Figure 10, provided with the reference RA, for the resetting of the accumulator A, Figure 1, is arranged on a key lever 515, which is disposed so as to be swingable on a shaft 516, mounted in bearings in the guide frame 238. The lever 515 by means of a bridge 517, is rigidly connected with the lever 518, which likewise is swingable on the shaft 516. On the lever 518, a lug 518a, is provided, to which one end of a spring 518b is attached the spring at its other end being connected to a lug, not shown, of the guide plate 238, whereby the lever 515 is held in its rest position, which is determined by the impact of the edge 515a, upwards against the guide plate 238. To the downwardly directed limb 515b, of the lever 515, a connecting rod 519 is jointed, which in turn, is jointed to a lever 520. This lever 520 is swingably mounted at the point 521 round a shaft, which is not shown. An arm 522 of the lever 520 acts with its part 522a upwards on an arm 523 of the two-armed clutch lever 100, which by means of its U-shaped part 100a, is swingably mounted on the screw 99. To an arm 523 of the clutch lever 100, a pin 524 is attached, to which pin one end of a spring 525 is connected, which at its other end is attached to a pin 526, provided on the machine frame, and holds the clutch lever 100 in its normal position, which is determined by the impact of a U-shaped lug 527 provided on the arm 523, of the clutch lever 100, on an intermediate wall of the machine frame. The nose 97 of the arm 98 of the lever 100 is connected in the already described manner, to the clutch 83. The face 520a of the lever 520, Figure 10, acts on the roller 292, provided on the lever 291, whereby the motor contact 300/302 is closed by means of the parts 291, 295 and 22.

The already mentioned lug 304 of the clutch lever 43, Figure 10, can enter into a recess formed by the noses 528 and 529, so that the lever 520 on the depression of the key 7, can swing round the point 521, without acting upon the clutch lever 43. The arm 531 of the lever 520 acts on a two-armed lever 532, Figure 10, which with its U-shaped part 533, at the point 534 is swingably mounted round a pin, not shown, arranged on the machine frame. The arm 535 of the lever 532, lies upwardly against a face 536 of a U-shaped lever 539, which is swingable round a screw 537 on a lever 538. On the lever 539 a

pin 540 is riveted, to which a spring 541 is attached which with its other end is connected to a pin 542 of the lever 538.

The spring 541 acts upon the lever 539 in the clockwise direction round the screw 537. Through contact of the face 536, of the lever 539, on the lever 532, which lies upwardly against the arm 531 of the lever 520, the normal position of the parts 532, 539 is determined. The U-shaped end 539a, of the lever 539, embraces a bar 544, fastened to the machine frame at the points 543. The angled lug 545, on the lever 539 may slide in a manner to be described later in detail on the bar 544.

The already mentioned lever 538 is rigidly mounted on the shaft 546, which is rotatably mounted in bearings in the machine frame. On the other end of the shaft 546, a further lever 547 is fixed in a similar manner, which by means of the screw 548 is in pivotal connection with the rod 109 of the resetting clutch 85.

The part 539a, of the U-shaped lever 539, on the depression of the resetting key 7, engages in the slots 549a (Figs. 4, 5, 6) of a comb 549, which is fixed on the resetting bar 550 of the accumulator A, Figure 1. The resetting bar 550 is displaceably mounted in the grooves 551a, Figure 7, of the boxes 551, which are provided on the rear wall Cr of the carriage C. Further, the resetting bar 550 is mounted in a ring groove sleeve 550b, attached to the rear wall Cr of the carriage C, Figures 4 and 8, by means of a screw 550a. By means of a spring 549c, which is attached at one of its ends to a pin 549b, Figure 4, of the comb 549, and at its other end, to an angle piece 552, Figure 8, of the carriage C, the resetting bar 550 is held in the rest position illustrated in Figure 4. The teeth 550d of the resetting bar 550, engage with toothed wheels 553, rotatable on the shafts 498. The toothed wheels 553 act on the toothed wheels 555 in case that the numeral wheels 554 of the accumulator A do not stand at "0" and the resetting bar 550 is actuated, which toothed wheels 555 are rigidly mounted on the numeral wheel shaft 556, on which likewise the numeral wheels 554 and the toothed wheels 557, 558 and 155 are rigidly mounted. If the numeral wheels 554 are at zero, the toothed wheels 555 fixed on the numeral wheel shaft 556 stand with their broad toothless spaces 555a, Figure 4, opposite to the spaces 553a (Figures 8 and 9) of the tooth wheel 553 formed by the removal of a tooth on half its tooth width. Therefore, the wheels 555, can rotate freely without acting upon the wheels 553 and in the rotation of the wheels 553 the wheels 555 remain inoperative, as soon as the numeral wheels 554 stand at zero, in which case the spaces 555a and 553a as shown in Figure 4 lie opposite to one another.

If on the other hand, the numeral wheels 554, Figures 8 and 9 of the accumulator A are not at zero, and if the resetting bar 550, Figure 4, is displaced in the direction of the arrow d, the wheels 555 and consequently the numeral wheel shafts 556, are rotated by the toothed wheels 553 in the direction of the arrow g, Figures 4 and 9. An overthrow action of the numeral wheel shaft 556 or the numeral wheel 554 in the direction of the arrow g beyond zero, is then prevented through the striking of the usual tens-carrying noses 155a, Figure 8, against the noses 155b, of the tens preparatory slides. The preventing of an overthrow action is particularly of importance in a power driven resetting device.

Resetting mechanism for the revolution counter

Near the resetting key 7, Figure 10, for the accumulator A, the resetting key 8 (Rrc) for the revolution counter RC is arranged. This is provided on a key lever 560, which is swingably mounted on the shaft 516. By means of a bridge 561, the key lever 560 is rigidly connected with a lever 562, similarly swingable on the shaft 516. By means of a spring, not shown, which at one end is attached to a lug 561a, formed on the bridge 561, and at the other end is connected to a lug, not shown, of the guide plate 238, the key lever 560 is acted upon in the anti-clockwise direction and held in its rest position, which is determined by the impact of the edge 560a of the key lever 560, upwards against the guide plate 238.

On the downwardly directed limb 563, of the lever 560, a connecting rod 564 is jointed, which is jointed also to lever 566, swingably mounted at the point 565. The arm 566a of the lever 566, acts with its part 566b upwards on arm 523 of the clutch lever 100. Into the recess 569, formed by the noses 567 and 568, the already mentioned lug 304 of the clutch lever 43, Figure 10, may enter, so that the lever 566 on the depression of the key 8, can swing round the point 565, in the clockwise direction without being impeded by the lug 304 of the clutch lever 43.

The arm 570 of the lever 566, acts on an arm 571 of the two-armed lever 572, which is swingably mounted on a screw 573 on the machine frame. On the screw 573 a two-armed lever 574, is also swingably mounted. By means of a spring 575, which is connected at one of its ends to a nose 576 of the arm 571, of the lever 572, and at its other end to a nose 578 of and arm 579 of the lever 574, the lever 572 is acted upon in anti-clockwise direction and the lever 574 in the clockwise direction, whereby the lug 579a, of the arm 579 of the lever 574 lies against a right angled bent lug 572a, of the arm 571 of the lever 572, and the normal position of the levers 572 and 574 in relation to one another is determined. On the arm 580, Figure 10 of the lever 574, a lug 581 is bent at right angles on its free end, which lug lies upwards against a lever 583 swingably mounted on a screw 582 on the lever 538. By means of a spring 584, which at one of its ends is connected to a pin 585, of the lever 583, and at its other end is attached to a pin 586 of the lever 538, the lever 583 is acted upon in the clockwise direction, round a screw 582, whereby the lever lies on the lug 581 of the lever 574. In this manner its normal position is determined.

The U-formed end of the lever 583 embraces a bar 588, fastened by means of screws 587 on the machine frame. The lug 589a, formed on the lever 583, may slide, on the bar 588, whereby the U-shaped part 589 may engage the grooves 590a, Figure 4, of a resetting bar 590, for the revolution counter RC and move this to and fro. The resetting bar 590 is displaceably mounted in grooves 590b, Figure 5, of both boxes 551, Figure 4, and is held upwards by means of screws 591 and parts 591a. By means of a spring 592, which at one of its ends is attached to the pin 593 on the bar 590 and at its other end to the left box 551, the bar 590 is held in its normal position, which is determined by the impact of the face 590x of the resetting bar 590 against the part 591a, provided on the left hand box 551.

The teeth 590b of the resetting bar 590 engage with twelve-toothed wheels 596, Figures 5 and 6,

each having one tooth removed to form a space 596a.

These toothed wheels 596 can engage with the ten-toothed wheels 597, rotatably mounted on the shafts 498, in which likewise through the removal of a tooth, a large space 597a is formed. On the wheels 597, cams 597b are fixed, which are able to move freely in semi-circular recesses 596b of the hubs 596c of the wheels 596, insofar as these take up the normal position represented in Figure 5. With the wheels 597, the wheels 206, Figure 9, are rigidly connected by means of the hubs 597c, which wheels 206 in turn engage with the wheels 208, 208a, etc., Figure 3, which latter are loosely rotatable on the numeral wheel shafts 556, and with the wheels 208', 208a', etc., Figure 3, and the numeral wheels 205, 205a, etc., of the revolution counter RC form a whole. Further, with the wheels 206 the tens carrying cams 209, 209a, etc., and by means of the sleeves 207, the star wheels 204, 204a, etc., are rigidly connected so that the parts 204, 207, 209, 206, 597c, 597 and 597b, also always rotate all together.

If these parts are rotated by the star wheels 204, the toothed wheels 597, Figure 5, all together with the cams 597b may rotate in each direction without acting on the resetting wheels 596.

If on the other hand the resetting bar 590 is displaced from the position represented in Figure 5, and moved into the position represented in Figure 6, and the spaces 597a are situated opposite to the resetting wheels 596, which is always the case if the numeral wheels 205 of the revolution counter RC stand at zero, the resetting wheels 596 may rotate without acting upon the wheels 597.

If the numeral wheels 205 of the revolution counter RC on the other hand are not at zero and if the resetting bar 590 is displaced out of the position according to Figure 5, and into the position according to Figure 6, the wheels 597 rotate until their spaces 597a stand opposite to the wheels 596.

It should be mentioned that the wheels 596 have 12 teeth and the toothed wheels 597 have ten teeth. This has the object to avoid an overthrow action of the numeral wheels 205 of the revolution counter RC in the following manner.

The throw of the resetting bar 590 is only of such an extent that it may rotate the wheels 596 through ten teeth only into the position illustrated in Figure 6, in this displacement of the resetting bar 590, the wheels 597 rotate always in the direction of the arrow h, whereby as soon as their spaces 597a lie opposite to the wheels 596 according to Figure 6, an overthrow action of the wheels in the direction of the arrow h could take place. This is, however, prevented by the striking of the cams 597b, fixed to the wheels 597 against the hubs 596c of the wheels 596, as shown in Figure 6. This overthrow lock is very important in conjunction with power driven resetting devices.

The operation of resetting mechanism for the accumulator is as follows:

The key lever 515, Figure 10, on the depression of the resetting key (R.A) 1, for the accumulator A is swung round the shaft 518 in the clockwise direction against the action of the spring 518b, engaging with the lever 518, which by means of the bridge 517, is in connection with the key lever 515. The connecting rod 519 jointed to the downwardly projecting limb, 515b, moves, in the opposite direction of the arrow a. The connect-

ing rod 519 swings the lever 520, jointed to it round the point 521, in the clockwise direction, whereby the arm 522, of the lever 520, with its part 522a, acts upwards against the arm 523 of the clutch lever 100 and in consequence of this swings it round the screw 99 in the clockwise direction. Here, the nose 97, of the arm 98, releases the nose 96 of the pawl 89 of the resetting clutch 83. Thereby the clutch pawl 89, Figure 2, under the action of its spring 95, is brought with its nose 101 into engagement with the tooth 102 of the clutch cam 84, fastened on the driving shaft 3, whereby the cam 84, the pawl 89, and consequently also the clutch housing 83, in which the pawl 89 is mounted by means of the pin 98, are carried along in the direction of the arrow e.

The arm 531 of the lever 520, acts in its swinging movement in the clockwise direction, on the lever 532, and swings this round its axis 534 likewise in the clockwise direction. Here, the arm 535 of the same acts upwards against the U-shaped end 539a of the lever 539, and swings this round the screw 537, against the action of the spring 541 in the anti-clockwise direction. Besides, the U-formed end 539a, of the lever 539, engages in the groove 549a of the resetting bar 550, Figures 4 and 7, lying directly opposite to it. In the swinging of the lever 520, Figure 10, the face 520a, acts on the roller 292, provided on the lever 291, and closes over the parts 294, 295, 22 30 already described in detail, the motor contact 300, 302, whereby now the motor commences to run in the direction of the arrow e!

As now the motor contact 300, 302 and the resetting clutch 83, Figures 2 and 10, were closed 35 by the release of the nose 96 of the pawl 89, through the clutch lever 100, the clutch 83, rotates in the direction of the arrow e, whereby the pin 108, fixed to the clutch disc 85, Figure 2, through the parts 109, 547, 546, 538, moves the 40 lever 539, Figure 10, to and fro whereby the lug 545 slides on the face 544g, of the part 544, whilst the lever 583, jointed to the lever 538, by means of the screw 582, slides with its U-formed part 589, on the face 588g of the part 588, with- 45 out exercising influence on any part.

As already described, the lever 539, Figure 10, moves to and fro, and is held in positive engagement with the slot 549a of the resetting bar 550, Figure 4, for the time being in consequence of 50 which this also is moved to and fro, and of course at the commencement always in the direction of the arrow d. In consequence of this, the resetting wheels 553 are rotated first in the anti-clockwise direction and turn the toothed wheels 555, in the clockwise direction and consequently, the co-operating numeral wheels 554, Figures 8 and 9, to zero.

If the resetting key 1 is held longer in the depressed position no damage is done, as here the 60 resetting wheels 553 are only idly moved to and fro by the rack 550, as they, in consequence of the toothed spaces 555a, Figure 4, once lying opposite to them, are unable to exercise any action on the toothed wheels 555.

In the swinging of the lever 520 in the clockwise direction, the nose 520g of the lever 520, acts on the angle lever 112 and swings this round its axis 111, against the action of the spring 115, in the clockwise direction. If the nose 520g has 70 released the lever 112, the same snaps under the action of its spring 115, behind the nose 520g of the lever 520, and holds this consequently in its swung-out position.

Approximately after one half revolution of the 75

resetting clutch 83, the pin 110 of the clutch 83 acts on the arm 112a of the lever 112, and swings this in the clockwise direction against the action of the spring 115. The lever 112 then releases the nose 520g, of the lever 520, whereby this under the action of the spring 518b, engaging the arm 518 of the key lever 515, returns as well as the remaining mechanism into their rest position.

10 This arrangement has the object in the case of too short strokes of the key 7, to hold the lever 520 outswung until the lever 539 with its lug 545, has run up on the bar 544g.

15 In the depression of the resetting key 7, for the accumulator A, the following are the locks which come into operation.

As already described the lever 520, Figure 10, has been swung in the clockwise direction. On this, the lug 304 of the clutch lever 43, Figure 10, 20 for the value entering clutch, and the carriage shift clutch engages with the recess 530 of the lever 520, whereby in the depression of an operating key, the clutch lever 43 cannot swing out, and in this manner cannot close either the value 25 entering clutch or the carriage shift clutch. The value entering and carriage clutches are not shown or described herein since they are not a necessary part of the invention but are disclosed in the previously referred to parent case.

30 The operation of the resetting mechanism for the revolution counter is as follows:

On the depression of the resetting key 8 (R_{RC}) for the revolution counter RC, the key lever 560, Figure 10 is swung round the shaft 516 against 35 the spring not shown, engaging with bridge 561, in the clockwise direction. The connecting rod 564, jointed to its downwardly projecting limb 563, moves, in the opposite direction of the arrow a. This swings the lever 566, jointed to it, 40 round the point 565 in the clockwise direction, whereby the arm 566a, of the lever 566, acts with its part 566b, upwards against the arm 523, of the clutch lever 100, and in consequence of this 45 swings it round the screw 99 in the clockwise direction against the action of the spring 525. The nose 97, of the arm 98, of the clutch lever 100, releases the nose 96 of the pawl 89, of the resetting clutch 83, whereby in the manner already described, the clutch 83 is closed.

50 The arm 570 of the lever 566, Figure 10, acts on the swinging of the lever 566, in the clockwise direction downwards on the arm 571 of the lever 572, and swings this then around the screw 573 in the clockwise direction. The spring 575 engaging with the arm 571, of the lever 572, swings therefore the lever 574, likewise in the clockwise direction, round the screw 573. The right angled bent end 581 of the arm 580 of the lever 574, acts upwards against lever 583, swingable on the lever 538, by means of the screw 582, and swings this against the action of the spring 584 in the anti-clockwise direction. The U-formed part 589 of the lever 583 engages in one of the slots 590a of the resetting bar 590, Figures 4, 7, lying directly 55 opposite to it.

55 In the swinging of the lever 566, Figure 10, in the clockwise direction, the edge 566, acts on the roller 292, arranged on the lever 291, whereby over the already previously mentioned parts 294, 70 295, 22, the motor contact 300, 302, is closed and the motor commences to run in the direction of the arrow e1.

As now the motor contact 300, 302, and the resetting clutch 83, Figures 2 and 10, by release 75 of the nose 96, of the pawl 89, are closed by the

clutch lever 100, the clutch 83 thus rotates in the direction of the arrow "e", whereby the pin 108 fastened to the clutch disc 85, Figure 2, through the parts 109, 547, 546, 538, moves the lever 583, Figure 10, to and fro, whereby the lug 589a slides 5 on the face 588g of the part 588, whilst the lever 539, jointed to the lever 538, by means of the screw 537, slides with its U-formed part 539a, on the face 544g, of the part 544, without exercising any action on any part.

10 As already described, the lever 583, Figure 10, moves to and fro, and is positively held in engagement with the slot 590a of the resetting bar 590 for the time being, Figures 4 and 7. Consequently also, this bar is moved to and fro, and at the commencement always in the direction of the arrow d. With this, the resetting wheels 596, Figure 5, are rotated out of the position represented in Figure 5, into that illustrated in Figure 6, and carry along with them all the toothed 20 wheels 597, not at zero, so far in the direction of the arrow h until the space 597a of the same lies opposite to the wheels 596, which is always the case, if the resetting bar 590 has taken up the position shown in Figure 6. As the wheels 597, 25 Figure 6, by means of the sleeve 597c, Figure 9, are rigidly connected with the wheels 206, and as these are in engagement with the wheels 208, the latter are rotated in the direction of the arrow g and rotate to zero the numeral wheels 205 30 rigidly connected with them of the revolution counter RC. An overthrow of the numeral wheels 205 beyond zero is prevented through the meeting of the cams 597b, Figure 6, on the hubs 596c 35 of the wheels 596.

Holding of the resetting key 8 depressed for a longer time does no damage, as hereby the resetting wheels 596 are only moved backwards and forwards idly by the rack 590, as they in consequence of the spaces 597a, lying opposite to them, 40 Figure 6, are no longer able to exercise any action on the toothed wheels 597.

In the swinging of the lever 566, Figure 10, in the clockwise direction, the angle lever 112 is able to snap behind the nose 566g, of the lever 45 566, and to hold this in its out-swung position. After approximately half a rotation of the resetting clutch 83, the pin 110 of the clutch 83, acts on the arm 112a of the lever 112 and swings this against the action of its spring 115, whereby 50 it releases the nose 566g of the lever 566, so that the lever 566, is returned into its rest position under the action of the spring (not shown) engaging with the lever 100.

This arrangement fulfills the same object as 55 resetting the key 7 above described. In the depression of the resetting key 8, for the revolution counter RC, the lockings which occur are the same as described with regard to the operation of the resetting mechanism for the accumulator.

Resetting mechanism for the keyboard

If the resetting key 6 (R_K), Figure 10, for the keyboard is depressed, the key shaft 505 acts on 65 the lever 511, whereby this is swung in the clockwise direction round the shaft 261. In this swinging, the resetting flap 318, fixed to the arm 511a of the lever 511 takes part. The resetting flap acts with its edge 318a on the projections 514a, 70 of the key locking bars 514. The key locking bars are moved against the action of its spring and the depressed keys released.

I claim:

1. In a calculating machine, a carriage, nu- 75

- meral wheels on said carriage, a mutilated gear wheel for each of said numeral wheels, a member common to all of said mutilated gear wheels to cause the latter to reset said numeral wheels to zero, a motor driven shaft, means operated by said shaft and movable into operative relation to said resetting member for actuating the latter, and means for moving the actuating means into operative relation with said resetting member in any position of the carriage.
2. In a calculating machine, a carriage, numeral wheels on said carriage, a mutilated gear wheel for each of said numeral wheels, a member common to all of said mutilated gear wheels to cause the latter to reset the numeral wheels to zero position, a motor driven shaft, and means including a clutch and operating members for operating said resetting member, a key, said clutch being controlled by said key and driven by said shaft, said operating members being operable by said clutch and engageable with said resetting member by said key upon depression thereof in any position of the carriage.
3. In a calculating machine, a carriage, numeral wheels on said carriage, a mutilated gear wheel for each of said numeral wheels, a member common to all of said mutilated gear wheels to cause the latter to reset said numeral wheels to zero, a motor driven shaft, means engageable with said resetting member for actuating the latter, and means for moving the actuating means into engagement with said resetting member in any position of the carriage, and a guide member, said actuating means including two members, one of the last mentioned members coacting with said guide member when the actuating means is in inoperative position and the other of said last mentioned members coacting with said guide means upon initiation of actuation of the actuating means to retain the latter in operative position.
4. In a calculating machine, a carriage, numeral wheels on said carriage, a mutilated gear wheel for each of said numeral wheels, a member common to all of said mutilated gear wheels to cause the latter to reset said numeral wheels to zero position, a motor contact, a motor driven shaft, a clutch on said shaft, a clutch lever for

said clutch, operating means connected with said clutch and engageable with said resetting member, a key operated three-armed lever, means operative to close the motor contact one of the arms of said lever being operative to actuate the closing means, the second arm operating said clutch lever, and the third arm being adapted to bring the operating means into engagement with said resetting member.

5. In a calculating machine, a carriage, numeral wheels on said carriage, a mutilated gear wheel for each of said numeral wheels, a member common to all of said mutilated gear wheels adapted to actuate the latter and reset the numeral wheels to zero position, a motor driven shaft, a clutch on said shaft, means operated by said clutch and engageable with said resetting member for actuating the latter, a clutch lever for said clutch, key controlled means for actuating said clutch lever and engaging said actuating means with said resetting means, and means for locking said key controlled means in operative position, and means on said clutch to release said locking means.

6. A calculating machine as claimed in claim 4 characterized by the provision of a pair of independently movable levers interposed between the third mentioned arm of said three-armed lever and said operating means, and yieldable means connecting the last mentioned levers together for resiliently imparting movement of one lever to the other lever and then to the operating means.

7. In a calculating machine, a carriage, numeral wheels on said carriage, a member common to all of said numeral wheels and operable to reset the latter to zero position, a motor driven shaft, such resetting member having slots therein, means operated by said shaft and engageable in said slots for actuating said resetting member, and means for moving said actuating means into operative relation with the slots of the resetting member in all positions of the carriage, said moving means including a yieldable connection permitting movement thereof under tension independently of the actuating means.

FRIEDRICH POTT.
